John F. Connell.

BY Chapin, Neal.

ATTORNEYS

UNITED STATES PATENT OFFICE.

JOHN E. O'CONNELL, OF SPRINGFIELD, MASSACHUSETTS.

PICKER OR FIBER-CLEANING MACHINE.

Application filed April 29, 1921. Serial No. 465,363.

To all whom it may concern:

Be it known that I, JOHN E. O'CONNELL, citizen of the United States, residing at Springfield, in the county of Hampden and State of Massachusetts, have invented new and useful Improvements in Picker or Fiber-Cleaning Machines, of which the following is a specification.

This invention relates to an improved picker or cotton cleaning machine. Its object is to more thoroughly clean the fiber, decrease the loss of fiber in the cleaning operation, more effectively control the passage of the fiber through the machine, more effectively separate the different elements taken out of the fiber so as to more easily reclaim waste material, and to generally improve this character of machine with respect to said objects together or separately.

According to my invention, I employ the same general arrangement as prior machines of like character with respect to a beater casing within which beater-bars may be rapidly rotated to open up the fiber and beat out the dirt and condensing rolls or cylinders to gather the cleaned fibers in a lap to be fed out of the machine. However, I provide a new relation of grid-bars and screening means for the dirt, and more particularly, a new arrangement for controlling the fiber and dirt as they each pass through the machine for separating one from the other. This control is obtained primarily by a new mode of directing and determining the currents of air through the machine to assist and improve its function. The changes in apparatus are incident to the principal plan of obtaining a better cleaning and saving of the fiber by the action of the air currents in the machine.

I will now describe my improved machine with reference to the accompanying drawings to enable one skilled in the art to thoroughly understand and practice the invention in its several aspects.

In the drawings,—

Fig. 1 is a longitudinal sectional view showing the parts of the machine arranged for operation according to one preferred plan of the invention;

Fig. 2 is a plan view of the machine in Fig. 1;

Fig. 3 is a view similar to Fig. 1, but with an additional structural and slightly modified operating feature; and

55

Fig. 4 is a plan view of the machine in Fig. 3.

Referring to Fig. 1: The cotton to be cleaned is fed into the beater casing 1 between the rolls 2. The beater-bars 3 are rotated at very high speed within casing 4 to open up the cotton fibers and beat out the dirt, motes, etc. The heavy dirt, foreign matter, and picker-seed fall between grid-bars 5 into the receptacle 7. The light lint, dust, and sand is taken from the beater casing through the screen 6 (by a strong current of air to be mentioned later) to be deposited in the chambers 8, 9, and 10, according to their gravity. The cleaned cotton, in its opened-up condition, is carried by a suitable air current over a settling or sand box 14 to condenser rolls 11 and 12. The latter are of usual screen construction, through which the air passes so that by 70 their rotation they may condense the cotton into a lap to pass out of the machine between rolls 13.

In carrying out my invention, I provide for two substantially independent currents 80 of air, separately controllable so as to have each act in its own particular manner on the cotton and the material beaten out of the cotton. With these two air currents and a suitable arrangement of apparatus to cause 85 the desired action on the separated material in the machine, I am enabled to keep more cotton in the machine for final delivery in the form of the finished product and to take more dirt from the cotton as it passes through the machine than other machines of this character. This result or the manner of accomplishing it is the principal object 90 of the invention and will be clear from a consideration of the air control about to be 95 described in connection with the apparatus and its operation.

The fan 16 draws air from beater cylinder 1 while fan 17 draws air through condenser rolls 11 and 12 through passages 50. Each 100 fan may be separately controlled to have the desired draft on its section of the machine. I am aware that other cotton cleaning machines or pickers have been provided with

two fans, but not with the same or like advantages as in my machine, as I will point out.

As shown by the arrows in Fig. 1, air for both fans 16 and 17 enters the machine between grid-bars 5. The air current prevents the cotton leaving the beater casing by this path along which the air enters. The grid-bars 5 can therefore be spaced wider apart than if the entering air did not hold back the cotton from being beaten out between them. The relatively heavy foreign matter such as picker seeds and motes, however, can readily fall against the air current and between the widely spaced grid-bars into settling compartment 7. The relatively light lint, dust, sand, etc., does not fall between the grid-bars for the same reason that the cotton does not fall. Therefore to separate this foreign matter from the cotton, the beater casing is provided with a screened section 6 separated from the grid-bars by the walls 19 and 20 of a settling chamber 9. Another settling chamber 8 is immediately below the screened section 6. Still another settling chamber 10 contains fan 16 and is connected by pipes 21 to settling chamber 9. As indicated in the drawings, chambers 8, 9, and 10 are closed up sufficiently to provide for fan 16 drawing air from beater casing 1 through screen 6 to chamber 8, through opening 22 to chamber 9, through pipes 21 to chamber 10, from which it is exhausted by the fan. The quantity of air can be readily controlled by the speed of the fan 16 or if preferred by the insertion of dampers 24 in the pipes 21, for the purpose of drawing all possible light foreign matter through screen 6 and away from the cotton being cleaned in casing 1.

The arrangement of grid-bars 5 and screen 6 with a suitable quantity of air moving through the latter, enables me to set the beater bars 3 very close to grid-bars 5 and screen 6, with improved results. As the air enters 5 the cotton is kept in the cylinder while beater bars 3 rake the fibers most effectively across the grids to beat out the heavier dirt. The air tends to hold the fibers against screen 6, while the bars 3 rake them along the screen, and the air forces the lighter dust, lint, etc., through the screen. The closer the beater bars to the grid-bars and screen, the better the raking action obtained.

The series of settling chambers 8, 9, and 10 separate the foreign matter according to gravity, and the relatively large chamber 10 containing the fan permits a final settlement of separated material so that any useful by-products are conveniently collected according to grade.

The fan 17 readily controls, according to its speed, the collection of the cleaned fibers into a desired uniform lap on condenser rolls

11 and 12. The air for this purpose assists in carrying the opened fiber from casing 1 over the sand box 14 to the condenser rolls.

The fan 16 is operated primarily for the special cleaning purposes which are available on account of the special construction incident to the purposes. The fan 17 is operated primarily for the purpose of properly collecting the fibers on the condenser rolls. I consider it of very substantial importance, and a feature of my invention, that the current of air for cleaning is not dependent in any substantial sense upon the current of air for carrying the fibers to and condensing them on screen rolls 11 and 12. According to my invention, each current of air is directed to its single purpose. In carrying out the purposes of each fan it will be understood that the inlet for air through the feed rolls and grid bar section 5 is large enough at all times to supply the full suction capacity of both fans so that at no time will said fans tend to work against one another in drawing out their respective currents of air. By this arrangement, I can control one current and the other current so that each will accomplish its own purpose and not interfere with the action of the other. By the separate control of the two air currents acting in conjunction with the apparatus having substantially the action as described, the cotton is much more effectively cleaned than in any machine of which I am aware after a long experience with such machines as are now in use. By doing more cleaning work in a cleaning machine of the character described, the more expensive carding machines which operate on the cotton fiber at a later stage in its manufacture have less cleaning to do and labor in renovating the carding machines as well as expense of new card clothing is saved.

The same improved machine already described is shown in Figs. 3 and 4 with a slight modification or addition which may be desired to increase the cleaning capacity of the beater casing under some conditions. The same reference numerals are used for the parts except upon the modified portion of the casing.

In the modification the casing 1 has an additional screen section 32 at the upper part of the casing, similar to screen section 6, and opening into space 40. The latter has a settling portion (at the right in Fig. 3) and is also connected at the top by means of vertical pipes 33 extending down each side of the casing to the settling chamber 9. These pipes 33 may be provided with dampers 34 as a means of controlling the flow of air from casing 1 through screen 32. Access is obtained to the beater bars by turning back the covers or walls of space 40 on suitable hinges as 30 and 31.

With the machine as constructed in Fig. 130

3, the operation due to screen section 32 can be used or not, as desired, by opening or closing dampers 34 in pipes 33. The advantage of the additional screen section 32 is due to the fact that it provides an increased working portion of the beater casing for the outlet dirt, particularly of the lighter varieties which tend to follow the beater bars in their exceedingly rapid rotation.

I have described my invention in one preferred form, the essential construction of which I have actually used with the advantages stated in the better cleaning of the cotton and control of the operation as a whole. My invention can be applied broadly to various specific types of cleaning machines of the character described.

What I described as my invention is:

1. In a machine of the character described, a beater casing and condenser rolls, a grid-bar section and a screen section for the casing, suction creating means to establish and control a current of air through said condenser rolls, separate suction creating means to establish and control a current of air inwardly through the grid-bar section and outwardly through said screen section, said two suction creating means being operated and controlled independently of one another.

2. In a machine of the character described, a beater casing and condenser rolls, a grid-bar section and a screen section for the casing, suction creating means to establish and control a current of air inwardly through the grid-bar section and outwardly through said condenser rolls, separate suction creating means to establish and control a current of air inwardly through the grid-bar section and outwardly through said screen section, said two suction creating means being operated and controlled independently of one another.

3. In a machine of the character described, a beater casing and condenser rolls, a grid-bar section and a screen section, a fan to draw air in through the grid-bar section and out through the screen section, and a second fan to draw air through the grid-bar section and out through the condenser rolls, said fans being operable to control said separate air currents independently of one another.

4. A cleaning machine having a beater casing provided with a plurality of outlets for dirt and a fan to draw air in one of said dirt outlets and out of the other, and a collecting means for cleaned material comprising condenser rolls and a second fan to draw said material out of the casing onto said condenser rolls, said fans establishing two independently controlled air currents in said machine.

5. In a cotton cleaning machine, a beater

casing having an outlet for cleaned fiber and provided in its peripheral wall with a grid-bar section and two dirt outlet sections, one above and one below said fiber outlet, and means comprising a fan to draw air in through said grid-bar section and out through both said dirt outlet sections.

6. A cleaning machine comprising a beater casing, a fan to establish a current of air through said casing to carry out the dirt, and a succession of settling chambers connected in series through which said air current passes in succession, the last one of the series containing the fan and of sufficient size for the fan to work therein and still permit an effective settling of the very light particles of dirt.

7. A cotton cleaning machine comprising in combination a cylindrical casing having an inlet for fiber to be cleaned and an outlet for cleaned fiber, rotatable beater bars in said casing, said casing having in its peripheral wall a grid-bar section adjacent the inlet and two additional screen outlet sections for dirt arranged one above and one below said cleaned fiber outlet so that said beater bars rake the cotton to be cleaned across said grid-bar section and said two screen outlet sections.

8. In a cotton cleaning machine, a beater casing having a grid-bar section and screen section and beater bars arranged to rotate very closely by the grid-bars, a condenser casing with condenser screens therein, connected to the beater casing to take the fiber therefrom, a fan arranged to draw air in through the grid-bar section and out through the screen section, and a second fan to draw the cleaned fiber from the beater casing onto the condenser screens, said fans being operable to control said separate air currents independently of one another.

9. In a cotton cleaning machine comprising, a beater casing and a condenser casing connected together, a grid-bar section in said beater casing, two fans, one for each casing, an independent air outlet from each casing to the air inlet of its respective fan, and a common air inlet for said connected casings through said grid-bar section.

10. A cotton cleaning machine including in combination a beater casing and a condenser casing connected together, said beater casing having a grid-bar section, and separate and independently controllable means to take air out of each casing, said grid-bar section affording an air inlet for both casings.

11. A cotton cleaning machine including in combination a beater casing having two dirt outlets one of which is used as an air inlet and the other as an air outlet, a condenser casing connected to the beater casing, an exhaust fan to take air out of said beater casing, and an independently operated ex-

haust fan to take air out of said condenser casing whereby the current of air through said beater casing can be controlled independently of the current of air through said condenser casing.

12. In a cotton cleaning machine, a beater casing having an outlet for cleaned fiber and provided with a grid-bar section and two dirt outlet sections, one above and one below said fiber outlet, means comprising a fan to draw air in through said grid-bar section, and out through both said dirt outlet sections, and a separately controlled fan for drawing air in through said grid-bar section and out through said cleaned fiber outlet.

13. A cotton cleaning machine comprising in combination a cylindrical casing having an inlet for fiber to be cleaned and an outlet for cleaned fiber, rotatable beater bars in said casing, said casing having in its peripheral wall a grid-bar section adjacent the inlet and two screen outlet sections for dirt arranged one above and one below said

cleaned fiber outlet so that said beater bars 25 rake the cotton to be cleaned across said grid-bar section and said two screen outlet sections, and suction creating means to draw air outwardly from said casing through said two screen outlet sections.

14. A cotton cleaning machine comprising in combination a cylindrical casing having an inlet for fiber to be cleaned and an outlet for cleaned fiber, rotatable beater bars in 30 said casing, said casing having in its peripheral wall a grid-bar section adjacent the inlet and two screen outlet sections for dirt arranged one above and one below said cleaned fiber outlet so that said beater bars 35 rake the cotton to be cleaned across said grid-bar section and said two screen outlet sections, and means to establish an air current into said casing through said grid-bar section and out of said casing through said two screen dirt outlet sections.

In testimony whereof I have affixed my signature.

JOHN E. O'CONNELL.
